CLAIM

The ornamental design for a bag with bottom corner handle, as shown and described.

DESCRIPTION

FIG. 1 is a front perspective view of the bag with bottom corner handle showing our new design.

FIG. 2 is a front elevation view thereof.

FIG. 3 is a rear elevation view thereof.

FIG. 4 is a right side view thereof.

FIG. 5 is a left side view thereof.

FIG. 6 is a top view thereof.

FIG. 7 is a bottom view thereof; and,

FIG. 8 is a detail view of the lower right corner of FIG. 1. The broken line showing of a rectangle is included for the purpose of illustrating the detail of the lower corner of the bag and forms no part of the claimed design.
